UNITED STATES PATENT OFFICE.

HARRY H. JONES, OF PORTLAND, OREGON.

RIFLE.

1,343,456.

Specification of Letters Patent. Patented June 15, 1920.

Application filed July 29, 1918. Serial No. 247,213.

To all whom it may concern:

Be it known that I, HARRY H. JONES, a citizen of the United States, residing at Portland, in the county of Multnomah and State 5 of Oregon, have invented certain new and useful Improvements in Rifles; and I do declare the following to be a full, clear, and exact description of the invention, such as will enable others skilled in the art to which

10 it appertains to make and use the same.

My invention relates to improvements in fire arms and more particularly to army rifles, although the invention could of course be used for other purposes. The principal 15 object of the invention is to provide an extremely simple and inexpensive, yet a highly efficient, durable, and in every way desirable rifle which will utilize the forms of expanding gases to drive the bullet from the barrel, 20 rather than necessitating the use of powder or other explosives for this purpose.

A further object is to provide a gun in which the gasoline or other fuel used is mixed with air and supplied to a combustion 25 chamber at the breach of the gun, thus making it unnecessary to provide cartridge cases for the bullets to contain the explosives for impelling them.

A still further object is to provide novel 30 means for mixing the fuel with air and forcing it into the combustion chamber.

Yet another object is to provide a single 35 operating member for actuating the bullet lifter which positions the bullets at the breech of the barrel, and for controlling the charging means of the combustion chamber.

With the foregoing objects in view the invention resides in the novel features of construction and unique combinations of parts 40 to be hereinafter fully described and claimed, the descriptive matter being supplemented by the accompanying drawings which form a part of this specification and in which:

Figure 1 is a central longitudinal section 45 of a gun constructed in accordance with my invention, showing a bullet in position to be fired from the barrel;

Fig. 2 is a view similar to Fig. 1, but illustrating the manner in which the bullet lifter 50 is lowered to receive the bullets from the magazine, this view also disclosing the manner in which the pump is operated to compress the mixture of air and fuel for supply to the combustion chamber;

55 Fig. 3 is a sectional view on the planes indicated by the line 3-3 of Fig. 1;

Fig. 4 is a vertical transverse section on the plane of the line 4-4 of Fig. 1;

Fig. 5 is a detail perspective view showing a portion of the valve which controls the 60 admission of explosive mixture to the combustion chamber;

Fig. 6 is a perspective view of the bullet lifter;

Fig. 7 is a side elevation of a portion of 65 the gun;

Fig. 8 is a sectional perspective view of the parts associated with the breech of the barrel;

Figs. 9 and 10 are perspective views of the 70 slide which operates the bullet lifter and the pump; and

Fig. 11 is a longitudinal section of the fuel reservoir and the means for mixing the fuel with air.

In the drawings above briefly described, the numeral 1 designates the barrel of the improved rifle, 2 designates the stock within which an electric battery and coil (not shown) are located for operating the spark 80 plug of the combustion chamber, and the numeral 3 refers to a breech casing connecting the stock and barrel. The front end of casing 3 is provided with a combustion chamber 4 located at the breech of the barrel 85 1 and preferably having a contracted front end 5 alined with said barrel. A throat 6

opens downwardly from the contracted portion 5 of the combustion chamber 4 and is adapted to snugly receive the head 7 of an 90 L-shaped bullet lifter L, when said lifter is raised to the position shown in Fig. 1, it being the office of said bullet lifter to lower, receive the bullets 8 from a bullet magazine 9, and then raise from the position of Fig. 95 2 to that illustrated in Fig. 1, thus locating the bullet at the breech of the barrel. From the head 7 of the lifter, an arm 10 extends rearwardly and is pivotally mounted at 11 in the casing 3, the opposite edges of said 100 arm having longitudinal cam grooves 12 in which studs or the like 13 on a slide 14 are received. By means of ribs 15 and grooves 16, or other preferred guiding means, the slide 14 is mounted in the lower portion of the casing 3 beneath the arm 10, and it will be observed that this arm inclines downwardly and forwardly. It will thus be seen that when the slide is moved rearwardly to the position of Fig. 2, the arm 10 and consequently the bullet lifting head 7 will be 110 lowered to receive a new bullet from the

magazine 9, whereas forward movement of said slide will raise the arm and head to locate the bullet at the breech of the barrel.

A reservoir 17 adapted to contain gasoline or other suitable explosive fuel, is mounted either fixedly or detachably in the rear end of the casing 3, and an air supply tube 17' discharges into said reservoir by means of a check valve 17'' (see more particularly Fig. 11). The front end of tube 17' carries a piston 18 (Fig. 11) upon which a pump cylinder 19 slides, the front end of said cylinder being connected at 20 to the slide 14, whereby each rearward movement of said slide will compress air in the cylinder 19 and force this air into the reservoir 17 through the tube 17' and its check valve 17''. This air leaves the upper portion of the reservoir 17 through a nipple 21 discharging into a valve casing 22 from which a tube 23 leads to an additional valve to be hereinafter described for controlling the discharge of mixture into the combustion chamber. A needle valve or the like 24 is provided in the casing 22 to allow and obstruct communication between the same and the tube 23. A fuel supply tube 25 is located in the reservoir 17 and leads from the bottom thereof into the nipple 21, being provided with a nozzle 26 located in said nipple but in spaced relation to the wall thereof. By this arrangement, when the air compressed in the reservoir 17 is allowed to escape, it forces outwardly through the nipple 21 and consequently draws a quantity of gasoline or the like through the nozzle 26, forming a combustible mixture which is carried by its own compression into the combustion chamber when the controlling valve is open. This valve is actuated by the movement of the slide 14 and it will be of course understood that any preferred means may be employed for actuating said slide. For illustrative purposes however I have shown an action rod 27 leading forwardly to a hand grip 28 which slides upon the bullet magazine 9.

The tube 23 above described leads to one end of a needle valve casing 29 communicating by ports 30 and a check valve 31 with the combustion chamber 4, the needle valve 32 of said casing being normally closed by a spring 33 as shown clearly in Figs. 4 and 5. A pinion 34 is secured on the outer end 55 of the valve 32 for coaction with a dog in the form of a spring 35 partly inset in one side of the slide 14. On the rearward movement of the slide, the spring slides idly over the pinion 34, but when said slide is forced forwardly sufficiently to raise the bullet lifter to the position of Fig. 1, the spring 35 engages and rotates the pinion 34, thus momentarily opening the valve 32 and permitting the escape of compressed air from the fuel reservoir 15, such escape of air car-

rying with it a quantity of gasoline or other fuel, in the manner above set forth. The explosive mixture thus compressed behind the bullet lifter is fired by means of a spark plug 36 to which electric current is supplied from a suitable battery and coil located in the stock 2, the wiring 37 connecting said spark plug with said battery and coil, being provided with a switch 38 which may be closed by trigger 39. 75

In operation, the magazine 9 is filled with the bullets 8 and the reservoir 15 with the gasoline or other fuel to be used. By now pulling rearwardly upon the hand grip 28, the bullet lifter is lowered to the position 80 of Fig. 2 to receive a bullet 8 from the magazine, and at the same time the pump cylinder 19 moves rearwardly to compress air in the reservoir 15. During this operation, the spring 35 has moved idly over the pinion 85 34 without in any manner affecting the needle valve 32. Forward movement of the hand grip 28 now shifts slide 14 again forwardly, thereby raising the bullet lifter to position the bullet 8 at the breech of the barrel 1, and when this has taken place, still further forward movement of the slide causes the aforesaid spring 35 to engage and rotate the pinion 34, thus opening valve 32 and permitting the compressed air to pick 95 up a quantity of fuel at the mixing device above described and carry such fuel into the combustion chamber through the tube 23. By the time the slide 14 has reached the limit of its forward movement, spring 35 100 has been disengaged from pinion 34 and the spring 33 again automatically closes the valve 32. When the trigger 39 is now pulled upon, the circuit of the spark plug is completed so that the charge is fired in the 10 combustion chamber 4 and the bullet 8 consequently is driven from the barrel. Whenever necessary the pump may be actuated without moving the bullet lifter, by giving short strokes to the hand grip, and the compression may thus be varied in the fuel reservoir and combustion chamber. 11

From the foregoing, taken in connection with the accompanying drawings, it will be obvious that although my invention is of 11 extremely simple and inexpensive nature, it will be highly efficient and in every way desirable. Since probably the best results are obtained from the details shown and described, they are by preference followed, 12 but within the scope of the invention as claimed, considerable latitude is allowed for making such changes as occasion may dictate.

I claim:

1. A gun comprising a barrel having at its breech a combustion chamber, a bullet magazine, a bullet lifter for feeding bullets from said magazine into said breech, a slide for operating said bullet lifter, a fuel res- 13

ervoir, a pump for compressing air into said reservoir, a combined air and fuel outlet and mixer for said reservoir, a tube leading from said outlet and mixer to said combustion chamber and having a valve, and means actuated by said slide for controlling said valve.

2. A gun comprising a barrel having at its breech a combustion chamber, a bullet magazine, a bullet lifter for feeding bullets from said magazine into said breech, a slide for operating said bullet lifter, a fuel reservoir, a passage from said reservoir to said combustion chamber having a valve, a pinion on said valve, and a dog on said slide for operating said pinion.

3. A gun comprising a barrel having at its breech a combustion chamber, said breech being provided with an inlet throat in its bottom, a vertically movable bullet lifter operating in said throat, and having a rearwardly extending arm, a magazine for supplying bullets to said lifter, a slide operatively engaged with said arm to raise and lower said lifter, an operating member for said slide, means actuated by said slide for charging said combustion member, and means for firing the charge.

4. A gun comprising a barrel having at its breech a combustion chamber, said breech being provided with an inlet throat in its bottom, a vertically movable bullet lifter operating in said throat and having a rearwardly extending arm provided with a cam groove, a magazine for supplying bullets to said lifter, a slide below said arm and having means traveling in said cam groove to raise and lower said arm, an operating member for said slide, means actuated by said slide for charging said combustion chamber, and means for firing the charge.

5. A gun comprising a fuel reservoir having an outlet nipple, a passage into which said nipple discharges, a fuel nozzle from said reservoir located in said nipple in 45 spaced relation to the wall thereof, a gun barrel, a combustion chamber at the breech of said barrel, a valve controlling communication between said passage and said chamber, means for feeding bullets to said 50 breech, means for forcing compressed air into said reservoir, and firing means for the mixture of fuel and air admitted into said combustion chamber.

6. A gun comprising a barrel, a casing 55 extending rearwardly from the breech of said barrel, a combustion chamber in the front end of said casing registering with said barrel, said combustion chamber having an inlet throat in its bottom, a vertically moving bullet lifter operating in said throat, an inclined arm extending rearwardly from said bullet lifter and pivotally mounted in said casing, a magazine beneath the barrel for supplying bullets to said 60 bullet lifter, a slide beneath said arm and operatively associated therewith for raising and lowering said bullet lifter when said slide is actuated, an operating member for slide, a pump in said casing in rear of 70 said slide and operated by the latter, a fuel reservoir in said casing into which said pump supplies compressed air, an air and fuel mixer from said fuel reservoir, a passage from said mixer to said combustion 75 chamber including a valve, means operated by said slide for controlling said valve, and firing means for the combustible charges admitted into said combustion chamber.

In testimony whereof I have hereunto set 80 my hand.

HARRY H. JONES.
